(57) **CLAIM**

(51) LOC (7) Cl. **13-03**

The ornamental design for an interconnect enclosure for computer and audio visual equipment mountable in a table top, as shown and described.

(52) U.S. Cl. **D13/139.4**

DESCRIPTION

(58) Field of Search ..... D13/139.4—139.8;

FIG. 1 is a perspective view of an interconnect enclosure for computer and audio visual equipment mountable in a table top with a lid in an open position. The broken lines are to illustrate an environment only and form no part of the claimed design.

174/48—49, 53, 58; 439/131, 135, 142,
650—654

FIG. 2 is a perspective view thereof with the lid in a closed position. The broken lines are to illustrate an environment only and form no part of the claimed design.

(56) **References Cited**

FIG. 3 is an enlarged top plan view thereof with the lid in the closed position; and,
